C. E. YOUNGBERG

CARDBOARD FIGURE

Filed March 31, 1921

INVENTOR
Carl E. Youngberg
BY HIS ATTORNEY

James F. Williamson

UNITED STATES PATENT OFFICE.

CARL E. YOUNGEORG, OF SEATTLE, WASHINGTON.

CARDBOARD FIGURE.

Application filed March 31, 1921. Serial No. 457,312.

To all whom it may concern:

Be it known that I, CARL E. YOUNGEORG, a citizen of the United States, residing at Seattle, in the county of King and State of Washington, have invented certain new and useful Improvements in a Cardboard Figure; and I do hereby declare the following to be a full, clear, and exact description of the invention, such as will enable others skilled in the art to which it appertains to make and use the same.

This invention relates to a toy cardboard figure, and particularly to such a figure having a striking and distinctive appearance which is adapted to be used as an advertising device to be placed in store windows and other places to attract the attention of patrons, and is also adapted for a variety of other uses.

It is an object of the invention to produce such a figure of peculiar and distinctive shape and which is so constructed that it will stand upright.

It is a further object of the invention to produce such a figure in which the head and arms are connected to the body portion by a single pivot and the leg portions are, likewise, connected to said body portion by a single pivot. The head, arms and legs being movable to various positions.

It is also an object of the invention to so construct the figure that it can be folded into a small space and thus easily transported or stored.

Other objects and advantages of the invention will appear from the following description made in connection with the accompanying drawings in which like reference characters refer to the same parts throughout the different views and in which—

Fig. 1 represents a view in front elevation of the device;

Fig. 2 represents a view in rear elevation;

Fig. 3 is a plan view of the device when folded together; and

Fig. 4 is a detail of the connecting means for the legs shown on an enlarged scale.

Referring to the drawings, the device comprises a body portion of narrow elongated shape with rounded ends to which is pivoted a head portion. This head portion is generally in the shape of a shield and is marked to simulate the face of a person and is surmounted by a cap shaped portion 2^a formed of the same sheet or piece of ma-

terial. In the particular embodiment of the invention shown, the cap is designed to represent a mariner's cap and is set with the peak disposed sidewise on the face portion. A pair of arms 3 and 3^a are secured to the body portion 1 by the same pivot that secures the head portion 2, these arms 3 and 3^a being formed as left and right arms, respectively. The said arms represent the sleeves of a mariner's coat and have expanded or bell-shaped lower portions and are formed with depending portions 4 at their lower ends, which simulate hands projecting from the sleeves. A pair of legs 5 and 5^a formed, respectively, as right and left members, are provided to represent trouser legs of a mariner's suit, and also have expanded or bell-shaped lower ends. Foot portions 6 and 6^a are formed of the same pieces of the sheet material as the arms 5 and 5^a and are of considerable extent lengthwise so as to form a base of larger area to support the figure. These portions are connected to the portions 5 and 5^a by narrow strips simulating the ankles of the person. The leg members 5 and 5^a are connected at their upper ends to a piece of fabric 7 of appreciable thickness and this fabric is pivoted centrally to the lower portion of the body member 1. The member 7 is formed with a central portion of substantially trapezoidal shape between the lines 7^a, which portion is adapted to contact with the body portion 1. Portions of the member 7 beyond the line 7^a is rigidly secured to the leg members 5 and 5^a. The member 7 thus forms a hinge connection by which the leg members are connected to the body member.

The members 5 and 5^a can be turned about the lines 7^a and can thus be brought into planes extending at an angle to the plane of the rest of the figure, so that the figure can be supported on the foot members 6 and 6^a, as shown in Figs. 1 and 2.

With this construction, and in the one embodiment of the invention shown the figure representing the mariner and which is called by the trade name of "Captain Cy," can be arranged to assume various poses. The arms 3 and 3^a can be moved to various positions about their pivot as can also the head member 2. The leg members 5 and 5^a can, likewise, be swung relatively to the body member 1, or vice versa, and the leg members moved about the hinged axes 7^a.

to various positions. When it is desired to store or pack the figure, the same can be collapsed into a small space, as shown in Fig. 3. It will be understood that the parts 5 are riveted together so that the same can be swung on the pivots but will be frictionally held in the position to which they are moved.

The figure has proven to be of great value 10 as an advertising device in attracting attention of customers. In use, the figure can be made to point to various signs or articles and to assume various amusing and ludicrous positions. The figure is also adapted for 15 a wide variety of other uses.

While in the particular embodiment of the invention illustrated the figure of a mariner is portrayed, it will be understood that the invention is not limited to any specific figure 20 or character.

Likewise the device can be made of any material which is found suitable in practice.

It will, of course, be understood that various changes may be made in the form, 25 details and arrangement of the device without departing from the scope of applicant's invention, which, generally stated, consists in the matter shown and described and set forth in the appended claims.

30 What is claimed is:

1. A figure made of flat sheet material constructed and arranged to stand erect and having in combination an elongated body portion, a head portion pivoted thereto adjacent its upper end, a pair of arms also pivoted to said body adjacent its upper end, said parts being connected by a single pivot extending normal to the plane of said portions on which they are movably and frictionally held in position, said portions being disposed in a plane which is normal to the direction in which the figure faces, flat leg portions secured to said body portion having feet at the lower ends, said leg portions 40 being movable about vertical axes with said feet, the feet forming the sole support for said figure.

2. A self-standing figure composed of sheet material comprising a head, arms, and 50 a body frictionally pivoted together at one point at the upper end of the body and legs frictionally pivoted to the lower end of the body carrying feet at their lower ends and hinged to swing at an angle thereto so that 55 said feet form supporting means for the same.

3. A figure representing a human being 60 made of flat material and facing a direction normal to the plane of said material comprising a narrow elongated body portion, a head member and a pair of arms pivoted thereto adjacent the upper end of said body portion and frictionally engaging said body portion so as to remain in the position to 65 which they are moved, and a pair of leg

members pivoted to said body portion adjacent its lower end having feet portions rigid therewith, said leg portions being formed of one piece and with said feet forming the sole support for said figure whereby 70 all of said parts can be swung substantially in alinement with said body to collapse said figure into a comparatively small area.

4. The structure set forth in claim 3, said leg members also being hinged adjacent said 75 body portion so as to move into planes intersecting the plane of said body portion.

5. A collapsible figure composed of sheet material comprising an elongated narrow body portion having rounded ends, a head 80 member and a pair of arm members pivoted thereto at its upper end by a single pivot, said parts being adapted to be moved in substantially the same plane, a pair of leg members connected to the lower end of the body 85 portion and being hinged to move into planes at an angle thereto, said leg members having elongated foot members at their lower ends adapted to rest on a flat surface and forming the sole support for said figure. 90

6. A figure comprising a body portion, head and arm members secured thereto, and a pair of leg members pivoted thereto for swinging movement relative to said body portion, said leg members also being hinged 95 adjacent said body portion to move into planes at an angle thereto and having feet at their lower ends with substantially horizontal bottom edges adapted to rest on a surface and form the sole support for said 100 figure.

7. A toy figure representing a human being being formed of thin flat rigid sheet material comprising a body portion, movable head and arms portions secured thereto, and a pair of leg portions secured to said body portion, said leg portions having feet at 105 their lower ends and being hinged about axes extending substantially vertical when said figure is standing, said figure being adapted to stand on a flat surface with said feet and legs forming the sole support thereof.

8. A toy figure made of flat material and comprising a body portion disposed normal to the direction in which the figure faces, 110 and a pivot member secured at the top and bottom portions thereof, respectively, and substantially at the transverse center thereof, a pair of arms and an elongated head portion connected thereto by the top pivot member, and a pair of legs connected thereto by the bottom pivot member, said arms, head portion and legs frictionally engaging said body portion and said legs forming the sole support for said figure. 115

9. A collapsible and adjustable toy figure made of flat sheet material comprising, an elongated body portion, said figure facing in a direction normal to the plane of said body portion, an elongated head portion on one 120

side of said body portion, superposed laterally extended arms on the other side thereof, said parts being connected by a single pivot passing therethrough and disposed centrally at the top of said body portion and passing through the bottom of said head portion, and a pair of legs connected to the bottom of said body portion swingable relatively to said body and each other about axes extending respectively substantially at right angles to each other.

10. A collapsible and adjustable toy figure comprising a body portion of sheet material disposed in a plane at right angles to the direction in which the figure faces, a head

portion, and arm portions connected to the upper end of said body portion to swing about an axis normal to the plane of said body portion, and a pair of leg members hingedly secured together and also connected to the body portion so as to swing as a unit about an axis normal to the plane of said body portion.

15 In testimony whereof I affix my signature in presence of two witnesses.

CARL E. YOUNGBERG.
